CIRCUIT INTERRUPTER

Herbert J. Crabbs, Wilkinsburg, Pa., assignor to Westinghouse Electric & Manufacturing Company, East Pittsburgh, Pa., a corporation of Pennsylvania

Application January 15, 1941, Serial No. 374,493

12 Claims. (Cl. 200—162)

This invention relates generally to electric circuit interrupters, and more especially to disconnecting switches.

As the size and capacity of disconnecting switches have increased in recent years, the contact pressures necessary to provide good electrical contact between the relatively movable parts of these switches have also necessarily increased, and one objection has been that such high contact pressures have rendered the switches difficult to operate, since all relatively movable parts are frictionally engaged under the aforesaid high pressures.

It has, accordingly, been found desirable to provide for easier operation of disconnecting switches by limiting the area of contact of the relatively movable parts of the switches, and by providing means for prying the switch blades loose in their opening movement. The instant invention is directed generally to improved constructions of disconnecting switches of this type, and one object of the invention is to provide a disconnecting switch with novel means for relieving the pressure on the separable contacts thereof when the switch is opened.

Another object of this invention is to provide a novel hinge contact construction for disconnecting switches.

Another object of this invention is to provide a disconnecting switch having limited area contact portions which are adapted to be entirely disengaged in a relatively minor portion of the movement of the switch to open the circuit.

Another object of this invention is to provide novel operating means for a disconnecting switch.

Still another object of this invention is to provide a novel type, and method of forming a limited area contact for circuit interrupters such as disconnecting switches.

These and other objects of this invention will become more apparent upon consideration of the following detailed description of preferred embodiments thereof when taken in connection with the attached drawings, in which:

Figure 1 is a side elevational view of a disconnecting switch embodying the invention;

Fig. 2 is a sectional view of the switch blade shown in Fig. 1, taken substantially on the line II—II of Fig. 1;

Fig. 3 is an enlarged side elevational view partially in section of the hinge end of the switch shown in Fig. 1, with one blade removed;

Fig. 4 is a partial sectional view of the break

contact of the switch shown in Fig. 1, and taken substantially on the line IV—IV of Fig. 1;

Fig. 5 is a fragmentary sectional view showing a preliminary step in the process of making the limited area contacts used in this invention;

Fig. 6 is a view similar to Fig. 5 but showing a completed contact portion;

Fig. 7 is a cross sectional view taken through the hinge contact of the disconnecting switch shown in Fig. 1;

Fig. 8 is a side elevation view partially in section similar to Fig. 3 but showing a slightly modified arrangement of limited area contacts at the hinge end of a switch;

Fig. 9 is a partial elevation view of a modified form of operating means and break contact for a disconnecting switch;

Fig. 10 is a partial cross sectional view of the switch shown in Fig. 9 and taken substantially on the line X—X of Fig. 9;

Fig. 11 is a side elevational view of a disconnecting switch similar to that shown in Fig. 1 but showing a modified form of hinge tongue for the switch, and illustrating the switch in a partially open position;

Fig. 12 is a cross sectional view of the hinge end of the switch shown in Fig. 11 taken substantially on the line XII—XII of Fig. 11; and

Fig. 13 is a partial cross sectional view taken substantially on the line XIII—XIII of Fig. 11.

Referring to the drawings, there is shown in Figs. 1 to 7 a disconnecting switch of the single-throw type embodying the features of this invention. The switch is adapted to be supported

on a pair of insulators 2 and 4, respectively, with the insulator 2 supporting the hinge contact tongue 6 of the switch, and insulator 4 adapted to support break contact tongue 8, with the contacts being rigidly secured to the insulators in

any desired manner such, for example, as by bolts or the like. The hinge contact tongue 6 is provided with a laterally extending terminal portion 10, and break contact tongue 8 is likewise provided with a laterally extending terminal portion 12, for connection of line conductors to the switch. A split switch blade 14 is pivotally connected to the hinge contact 6 by a pivot bolt 18 passing through the blade and hinge tongue. The blade 14, as stated, is of the split type and

includes the pair of side blades 16 positioned at opposite sides of the hinge tongue. A pressure determining sleeve 20 is provided over pivot bolt 18 and between the head of bolt 18 and nut 22.

At the outer sides of the switch blade 14 there are provided coil compression springs 24 adapted to

be compressed by nut 22 and thereby bias the blade sides 16 into engagement with the hinge contact tongue 6. It will be noted that sleeve 20 acts to determine the maximum pressure which may be exerted on the blade sides, inasmuch as it is impossible to turn down nut 22 on the bolt more than the distance predetermined by the length of sleeve 20. Both the hinge contact tongue 6 and blade sides 16 are provided with projecting, limited area contact portions 26, which may be constructed in a manner to be hereinafter described.

The contact portions 26 are preferably arranged on opposite sides of the hinge tongue and may be substantially rectangular in form as shown in Fig. 3, and extend substantially radially with respect to the blade pivot bolt 18. A spacing washer 28 is provided between each blade side 16 and hinge contact tongue 6. The spacing washers 28 are of less thickness than the distance between the blade sides 16 and hinge contact tongue 6 when the raised contact portions 26 are in engagement. However, the washers 28 are of greater thickness than the projecting portion of each limited area contact 26, so that when the blade 14 is moved from the closed circuit position shown in Fig. 1 to an open circuit position wherein the limited area contact portions 26 on the blade and contact tongue are out of alignment, the blade sides 16 will be biased by coil springs 24 into engagement with spacing washers 28, while the limited area contact portions 26 will thereby be maintained out of engagement and will not be subjected to any frictional rubbing engagement during the major portion of the opening movement of the switch. In other words by the hinge contact construction illustrated, the contact portions of the blade and hinge contact tongue are engaged only adjacent the closed position of the switch and are entirely disengaged after a relatively minor portion of the movement of the switch blade in a direction to open the switch.

Break contact tongue 8 is provided with a slot 30 in its outer end, which slot is provided at its outer end with a divergent portion for receiving the connecting bolt 32, connecting blade sides 16 at this end of the switch. The bolt 32 is, like pivot bolt 18, provided with a pressure limiting sleeve 34 between the head of the bolt and nut 36 to limit the pressure which can be exerted on coil springs 38 positioned at the outer sides of the blade and engageable by the head of the bolt and nut 36. A spacing sleeve 40 is provided over sleeve 34 between blade sides 16, and is of a length such that when the limited area contact portions of the blade and break tongue limited area contacts 42 are in engagement, the blade sides 16 are then apart a greater distance than the length of sleeve 40.

The sleeve 40 has the same function as spacing washers 28 at the hinge end of the switch in that it prevents contact of the blade contact portions 42 with the break contact tongue, and also prevents engagement of the break contact tongue limited area contact portions 42 with the switch blade when the contact portions 42 are moved out of engagement when the switch is opened. Obviously, when the switch is opened and moved from the position shown in Figs. 1 and 4, contact portions 42 will, upon a slight movement of the blade in a counterclockwise direction, be entirely disengaged, for example, as shown in Fig. 11, and at this point coil compression springs 38 move the blade sides 16 inwardly into engage-

ment with spacing sleeve 40, thereby maintaining the contact portions 42 out of engagement, so that substantially no friction can be encountered at the break end of the switch upon continued movement of the blade to its open circuit position.

The break contact tongue 8 is provided with integral spaced supporting wall portions 44 (only one of which is shown) for supporting therebetween a latch lever 46 pivotally mounted on a pin 45 supported by walls 44. The latch lever includes an upper latching portion 48 adapted to hook over a latch pin 50 passing through blade sides 16, to lock the blade in its closed circuit position, wherein the contacting portions 42 and 26 thereof engage the corresponding contacting portions on the hinge and break contact tongues. The opposite end of latch lever 46 is provided with a toe 52 adapted to engage a portion of contact tongue 8 to limit movement of the latch lever in a clockwise direction about pivot pin 45. The latch lever is also provided with a shoulder 56 against which is seated a coil compression spring 54, which bears upon the contact tongue 8 to urge the latch lever in a clockwise direction about its pivot pin 45.

An operating lever 58 is pivotally mounted intermediate its ends between the sides 16 of switch blade 14, on a pivot bolt 60 passing through the blade. The outer end of this operating lever is provided with an aperture 62 for the reception of a hook stick or other operating member. The inner end of the operating lever is provided with a cam engaging portion 64 adapted to engage the curved cam surface 66 provided at the upper end of latch lever 46. Intermediate the inner end of operating lever 58 and its pivot bolt 60, there is provided an enlarged aperture 68 through which is passed a headed pin 70 which extends freely through the aperture 68 and is closely fitted in apertures in the blade sides 16. The upper edge of aperture 68 in operating lever 58 is tapered in form to provide opposed inclined surfaces 72 which are adapted to cooperate with the inward extending rounded heads of the cam rivets 74, provided on each blade side 16 as is more clearly shown in Fig. 2.

In operation, when it is desired to open the switch shown in Figs. 1 to 7, the operating lever 58 is moved in a counterclockwise direction. This will cause the inner end 64 thereof to move latch lever 46 in a counterclockwise direction to clear latch pin 50 until the latch lever 46 moves into engagement with break contact tongue 8. At the same time, the inclined surfaces 72 on the upper edge of aperture 68 in latch lever 58 will engage the enlarged heads of cam rivets 74 and force them, together with blade sides 16, laterally outwardly away from each other, and consequently move the limited contact portions 42 on the plate out of engagement with respect to the contact portions on break contact tongue 8. All this is accomplished without any substantial pivotal movement of the blade about pivot bolt 18 until, as stated before, latch lever 46 is moved into engagement with break contact tongue 8, and at about the same time this occurs, the upper edge of aperture 68 will engage pin 70 connecting blade sides 16, thereby stopping pivotal movement of the operating lever about its pivot pin 60, whereupon a continued pull on operating lever 58 in the same direction will cause movement of switch blade 14 therewith about its pivot 18 away from break contact 28, to insert a relatively large air gap in circuit. It can be

seen that before any attempt is made to pivotally move the blade in opening the switch, the sides of the blade are first moved laterally out of engagement with the hinge contact tongue by force multiplying means, that is, cam surfaces 12 and cam rivets 14, so that there will be substantially no friction opposing opening movement of the blade at the break end thereof.

Furthermore, after the contacting portions 42 at the break end of the switch have been moved laterally out of engagement with each other, a continued pull on operating lever 58 provides a pry-out action to start movement of the contacting portions 26 at the hinge end of the blade, and since these contacting portions are also moved out of engagement with the contacting portions on the hinge tongue in a relatively minor portion of the path of opening movement of the switch blade, it is readily apparent that the major portion of the opening movement of the switch will be very easy, and will be substantially frictionless. It should be noted that the pry-out action is not necessary to disengage the break contacts, but is useful mainly in overcoming friction between the contacts at the hinge end of the switch, and this is rendered substantially effortless because of the long lever arm available to move the hinge contacts. It will also be noted that there is no sliding friction necessary in opening the switch between the contact portions 42 on the switch blade and break contact tongue. At the hinge contact the only sliding friction encountered by the contacting portions 26 is merely that necessary to move these portions out of alignment with each other which, as will be readily apparent, is but a very minor portion of the movement of the switch in its circuit opening operation.

The limited area contact portions 26 and 42 heretofore described may be formed in a variety of different ways; as shown in Fig. 4, they may be mounted in slots cut in the blade or contact tongue and secured therein in any desired manner such, for example, as by soldering, brazing or the like. Furthermore, these contact portions may have substantially flat contacting surfaces if desired, but preferably the contact portions are of a shape and are constructed in a manner such as illustrated in Figs. 5 and 6 of the drawings. This preferred form of limited area projecting contact construction is provided in the following manner.

As shown in Fig. 5, a layer of a noble metal 18, such as, for example, silver or the like, is preferably secured on the switch member 16, which may be a portion of the switch blade or contact tongue, in any desired manner such, for example, as by spraying or plating, or the like. After the strip 18 is secured to the switch member, the edges thereof are subjected to a pressing operation to press the edges into and below the surface of the contact member 16 as at 80, thereby effecting a cold flow of the metal 18 towards the center thereof and away from its edge portions, to form a projecting central portion 88 which, as shown in Fig. 6, is preferably arcuate in form so as to form a substantial line contacting portion of a noble metal which projects beyond the surface of the adjacent switch member. The method of forming a limited area projecting contact portion described above has the advantage that by subjecting the contacting material 18 to a pressing operation to effect a cold flow of the metal, there is not only formed the desired form of a rounded contact portion, but

also at the same time this acts to harden the material 18 and improve the closeness of the grain thereof, to thereby provide a smooth hard and close grained contact portion, which is highly desirable in switches of this type.

In Fig. 8 there is illustrated a slightly modified form of hinge contact construction, and since most of the parts are like those previously described in connection with the embodiment of Figs. 1 to 7, like numerals will be used to designate these like parts. This embodiment of the invention differs from that previously described only in the shape of the limited area contact portions 82. As shown in Fig. 8, these are substantially circular in form and are spaced from each other and from the pivot bolt 18 of the switch. The contacting surface of the portions 82 may, like those previously described, be substantially flat or arcuate in form, preferably the latter, so that a plurality of point contacts are obtained between the switch blade and the hinge contact tongue, which, due to their different radial positions relative to the pivot bolt 18, are entirely disengaged upon a relatively minor portion of the opening movement of the switch blade, to thereby reduce the friction on these portions 82 in substantially the same manner in which the hinge contact portions 26 are disengaged in the embodiment previously described. In view of the similarity between these embodiments of the invention, the operation of the construction shown in Fig. 8 is believed to be obvious and, accordingly, will not be repeated.

In Figs. 9 and 10 there is shown a slightly modified break contact and operating mechanism construction. Here also like numerals will be used to designate parts like those previously described. In this embodiment of the invention a break tongue 84 is employed having the upper end thereof cut off at an angle, with a slot 86 opening at the upper end thereof for receiving bolt 32 provided on the switch blade. Limited area raised contact portions 88, similar to the portions 42 and 26 previously described, are provided on the blade and contact tongue, but, as shown, these portions 88 are provided on opposite sides of slot 86 and in substantial alignment, so as to lie at the same angle to the direction of movement of the blade adjacent the break contact tongue 84. It is believed obvious that the contact portions 88 will, like the portions 42, be engaged and disengaged by very slight movement of the switch blade at its fully closed position. The switch shown in Figs. 9 and 10 is adapted to operate by remotely controlled means having an operating rod 90 extending into a socket 92, of an operating member 94 adapted to be operatively associated with the switch blade. This operating member 94 is provided with an elongated aperture 96 for receiving a pin 98 similar to the pin 70 previously described, and in this case the lower edge of the aperture 96 in member 94 is provided with opposed converging cam surfaces 102 adapted to cooperate when the switch is opened with the enlarged rounded heads of cam rivets 100.

The operation of the embodiment of this invention shown in Figs. 9 and 10 is very similar to that previously described, in that when it is desired to open this switch, the operating rod 90 is pulled outwardly, thereby causing the cam surfaces 102 to engage cam rivets 100 and move the sides 16 of the switch blade relatively outwardly so that the limited area contact portions 88 thereof move out of engagement with the corresponding portions on break contact tongue 84, where-

upon the switch may be readily pivotally moved to its complete open circuit position. This operation is essentially the same as that previously described and is adapted for use especially with a remotely operated switch operating means.

In Figs. 11 to 13, there are illustrated views of a disconnecting switch much like that shown in Figs. 1 to 7 but embodying a slightly modified form of hinge contact construction. In this embodiment of the invention the hinge contact tongue 103 is of skeleton form and embodies a central thickened portion 106 through which pivot bolt 18 passes, and has contact supporting arms 104 extending substantially radially from pivot bolt 18, instead of the solid tongue construction shown in Fig. 1. The arms 104 of the hinge contact tongue shown particularly in Figs. 12 and 13 may have inserts 108 of silver or other noble metal substantially flush with the surface of the arms, while blade sides 16 have punched out portions 110, the projecting inner surface of which may be coated with silver 112, or some other noble metal preferably in the manner disclosed in connection with Figs. 5 and 6.

In Fig. 11, the switch is illustrated in a partially open position, that is, the position in which the operating lever 58 has been operated to the point wherein it has laterally separated blade sides 16, released latch lever 46 from locking pin 50, and has pried the blade open to the position shown in Fig. 11, where the latch lever is prevented from further rotative movement in a counterclockwise direction about its pivot pin 60 by engagement of latch lever 46 with break contact tongue 8, and the upper edge of aperture 68 through the operating lever may also be in engagement with stop pin 70, so that continued movement of the operating lever 58 in the same direction will cause movement of the switch blade 14 therewith about its pivot 18 to a fully open position, wherein a large air gap is inserted in the circuit.

Referring again to Fig. 11, it will be noted that although in this figure the limited area contacts 108 and 112 are not entirely disengaged, they have been slightly moved out of alignment by the prying-out action of actuating lever 58, and that upon further movement of the blade toward its fully open position, these limited area contacts 108 and 112 will be entirely disengaged in a relatively minor portion of this movement. It can be seen that as soon as the contact portions 108 and 112 are moved out of alignment, coil springs 38 will move the blades at the hinge end thereof together against the thickened portion 106 of the hinge tongue, and that the limited area contact portions 112 on the blades will lie opposite the spaces between adjacent arms 104 of the hinge contact tongue.

From the foregoing, it is obvious that in this embodiment of the invention, as well as in those previously described, the only frictional rubbing contact of the limited area contacts at the hinge end of the switch is no more than that necessary to move the contacts a distance equal to the width thereof which obviously is a mere minor portion of the movement of the switch blade in a circuit opening or closing operation. During the remainder or major portion of the movement of the switch blade in a circuit opening or closing operation, the limited area contacts 112 on the blade, as stated above, will be positioned opposite the spaces between contact tongue arms 104 and, therefore, out of engagement with any portion of the contact tongue, whereas the limited area contact portions 108 on the contact tongue will

be maintained in spaced relation with respect to the blade by engagement of the central portion of the hinge end of the blade with the thickened central portion 106 of the hinge contact tongue. Inasmuch as the operation of the switch actuating lever and the manner in which it relieves the pressure on the break contacts is identical with that previously described in connection with the embodiment of the invention shown in Figs. 1 to 7, it will not be repeated here.

From the foregoing it is apparent that this invention provides a novel form of raised limited area contacts for a disconnecting switch or other circuit interrupting means, with a special arrangement of such contacts at the hinge end of a disconnecting switch to limit rubbing of the contacts to a very small movement of the switch, and a special arrangement of operating mechanism in connection with limited contacts at the break end of the switch whereby substantially no frictional rubbing engagement takes place between the contacts at this end of the switch, thereby rendering the entire switch extremely easy of operation while providing high pressure limited area contact of the relatively movable parts of the switch in the closed circuit position.

Having described preferred embodiments of the invention in accordance with the patent statutes, it should be understood that although preferred embodiments thereof have been described in detail, the invention should not be limited to these particular embodiments, inasmuch as it will be obvious to persons skilled in the art that many changes and modifications may be made in these particular embodiments without departing from the spirit and scope of this invention. Therefore, it is desired that the invention be interpreted as broadly as possible, and that it be limited only by the prior art and by what is specifically set forth in the following claims.

I claim as my invention:

1. In circuit interrupting means, a split switch blade mounted for movement into and out of engagement with a cooperating contact, an operating lever pivotally mounted on said blade and having an apertured portion, one edge of said lever aperture having opposed cam sides, and cam projections on said blade sides, respectively, and projecting into said aperture so as to be engageable by said cam sides upon movement of said lever in one direction to separate said blade sides, means carried by said blade and extending through said lever aperture for limiting movement of said lever relative to said blade, whereby continued movement of said lever causes movement of said blade therewith away from said cooperating contact to insert a relatively large gap in the circuit.

2. In a switch, spaced hinge and break contact members, a blade member pivotally mounted on said hinge contact member for movement into and out of engagement with said break contact member, the engaging portions of said blade and hinge contact member at the closed position of said switch comprising, limited area raised contacting portions on each of said blade and hinge members, said contacting portions being spaced about the pivot axis of said blade, and means limiting movement of said blade and hinge members toward each other at other switch positions to prevent said contacting portions of each member from engaging the other member except when said switch is substantially closed.

3. In a switch, spaced hinge and break contact members, a blade member pivotally mounted on

said hinge contact member for movement into and out of engagement with said break contact member, the engaging portions of said blade and hinge contact member at the closed position of said switch comprising, elongated limited area raised contacting portions on each of said blade and hinge members, said contacting portions being spaced about the pivot axis of said blade and extending substantially radially with respect to said axis, and means limiting movement of said blade and hinge member toward each other at other switch positions to prevent said contacting portions of each member from engaging said other member except when said switch is substantially closed.

4. In a switch, spaced hinge and break contact members, a blade member pivotally mounted on said hinge contact member for movement into and out of engagement with said break contact member, the engaging portions of said blade and at least one of said contact members comprising at least one raised, limited area contacting portion on one of said members, said portion having an outer surface of a hardened noble metal with the outer edges thereof pressed to a thickness less than the central part thereof to a position below the surface of the member on which it is mounted.

5. The method of making an electrical contact member with a projecting limited area contacting portion, including the steps of providing a layer of a noble metal on one surface of said member, and then pressing only edge portions of said metal into the material of said member to a position below the surface of said member in a manner to effect a cold flow of said metal inwardly from the edge portions thereof and outwardly with respect to said member.

6. The method of making an electrical contact member with a projecting limited area contacting portion, including the steps of adhering a layer of a noble metal on said member, and then working said metal cold to effect a flow of said metal from edge portions thereof toward the center to provide a raised central portion and thin edge portions.

7. In a switch, spaced hinge and break contact members, a blade member pivotally mounted on said hinge contact member for movement into and out of engagement with said break contact member, the engaging portions of said blade and hinge contact member comprising, limited area raised contacting portions on both of said members, said contacting portions being spaced about the pivot axis of said blade and arranged to be engaged in the closed position of the switch, means biasing said blade and hinge contact member laterally into engagement to urge the contacting portions thereof into engagement under pressure, and means limiting movement of said members towards each other under the influence of said biasing means at other position of the switch to a distance such that said contacting portions of each member are prevented from engaging the other member at said other switch positions.

8. In a switch, spaced hinge and break contact members, a blade member pivotally mounted on said hinge contact member for movement into and out of engagement with said break contact

members, the engaging portions of said blade and hinged contact member comprising, limited area raised contacting portions on one of said members, with said contacting portions spaced about the pivot axis of said blade, the other of said members including limited area spaced contact arms extending radially from said pivot axis and positioned to engage said contact portions only substantially at the closed position of said switch.

10. 9. The method of making an electrical contact member with a projecting limited area contacting portion, including the steps of providing a flat layer of a noble metal on said member, and then pressing solely opposite edge portions of said metal toward said member to decrease the thickness of said edge portions and thus provide a central limited area contact portion.

10. In a switch, spaced hinge and break contact members, a blade member pivotally mounted on said hinged contact member for movement into and out of engagement with said break contact member, the engaging portions of said blade and hinge contact member at the closed position of said switch comprising, a pair of limited area raised contacting portions on each of said blade and hinge members, the contacting portions of each pair being located at opposite sides of the pivot axis of said blade, and means limiting movement of said blade and hinge member toward each other at other switch positions to prevent said contacting portions of each member from engaging the other member except when said switch is substantially closed.

11. In circuit interrupting means, a split switch blade mounted for movement into and out of engagement with a cooperating contact, an operating lever pivotally mounted on said blade and having an apertured portion, one edge of said lever aperture having at least one cam side, and a cam projection on the blade side adjacent said cam side projecting into said aperture so as to be engageable by said cam side upon movement of said lever in one direction to separate said blade sides, means carried by said blade and extending through said lever aperture for limiting movement of said lever relative to said blade, whereby continued movement of said lever causes movement of said blade therewith away from said cooperating contact to insert a relatively large gap in the circuit.

12. In a circuit interrupting means, a split switch blade mounted for movement into and out of engagement with a cooperating contact, an operating lever pivotally mounted on said blade between the sides thereof and having an aperture portion, one edge of said lever aperture having opposed cam sides, cam projections on said blade sides, respectively, and projecting into said aperture so as to be engageable by said cam sides upon movement of said lever in one direction to separate said blade sides, a pin connecting said blade sides and extending through said aperture for limiting movement of said lever relative to said blade, whereby continued movement of said lever causes movement of said blade therewith away from said cooperating contact to insert a relatively large gap in the circuit.
